BOWLING BALL GRIP

Thomas R. Uhas, San Antonio, Tex.

Application November 3, 1950, Serial No. 193,816

1. Claim. (Cl. 273—63)

1

The present invention relates to a standard bowling ball which is thought to be an obvious advance and improvement in the art of bowling ball constructions in that it has what is thought to be a superior and far more efficient grip.

It is a matter of common knowledge to those skilled in the art to which the invention relates that bowling balls are made to provide two-fingered to four-fingered grips. Therefore, a bowling ball may be pictured, in its simplest form, as having at least two properly angled sockets one forming a so-called finger hole and the other a thumb hole. Naturally, the holes are of different lengths and diameters. Generally, the common finger hole is cylindrical in cross-section although other cross-sectional shapes have been appropriated for use. Nevertheless, and notwithstanding the efforts of manufacturers to produce finger holes best suited for overall efficient gripping results, the way for improvements is still clear. In the circumstances, an object of the present invention is to provide finger holes which have diametrically opposite substantially flat converging walls. The walls converge toward what may be described as the inner palmar wall of the hole and when the ball is gripped and swung, the weight of same and the tendency to "squeeze" the ball, causes the fingers to wedge and thus more securely lodge themselves in the holes, whereby to bring about a more sure and reliable grip.

Another object of the invention is to have the converging wedging walls of the respective holes converge toward the crown portion of the ball so that the squeeze action causes the fingers to approach each other and further equalizes and insures a desired and efficient grip, yet allowing the fingers to be eased out of the holes when the bowler releases the ball.

A more general object of the invention is to improve as far as possible on known bowling ball grips and to provide a ball in which manufacturers and bowlers will find their expected needs fully met and effectually available.

Other objects and advantages will become more readily apparent from the following description and the accompanying illustrative drawings.

In the accompanying sheet of drawings wherein like numerals are employed to designate like parts throughout the views:

Figure 1 is a top plan view of a bowling ball having the improved grip herein covered;

Figure 2 is an enlarged fragmentary section taken on the approximate line 2—2 of Figure 1, looking in the direction of the arrows;

2

Figure 3 is an enlarged fragmentary section taken on the line 3—3 of Figure 1, looking in the direction of the arrows; and,

Figure 4 is a horizontal fragmentary section on the line 4—4 of Figure 3, also looking in the direction of the arrows.

The ball which is conventional, is denoted by the reference character A and the index finger hole is denoted at B, the second finger hole at C, and the thumb hole at D.

Except for proportions each finger hole B, C or D, as the case may be, is the same in construction. It is thought that it will simplify matters by describing a single hole. To this end and although the hole, in end view, appears to be of general triangular form, it may be basically visualized, it is believed, as approximately trapezoidal in cross-section and characterized by two opposed diverging flat side walls 6 and 8 and inner and outer transverse walls 10 and 12, respectively. The walls 10 and 12 are of curved or arcuate form as depicted in the drawings. It is believed that insofar as the outer wall 12 is concerned it is of no significance except that it functions to locate the finger, confines it and affords unrestrained clearance as it "slips out" of the hole. However, the inner palmar wall 10 is not only relatively narrow but is preferably concave to conform to the fleshy part of the finger on the palmar side of the finger. The finger appears in phantom lines and is denoted at E in the drawings.

The principal surfaces are three and these are the opposed substantially parallel flat converging walls 6 and 8 and the narrower palmar wall 10. The three walls form a wedge-shaped pocket and when pressure is applied on the finger during the time of taking the grip on the ball, the fleshy part of the finger rides into the constricted portion of the pocket and the finger is thus frictionally jammed and lodged in place. The idea is not to cram the finger in the crotch to a point that it will become cramped and immobile. On the other hand, the degree of divergence of the walls 6 and 8 should be such that the finger becomes firmly lodged in the crotch. Obviously, with a three-holed ball and with the holes having the wedging walls herein shown and described, a firm grip is had and the grip becomes more secure as the ball is squeezed between the several fingers while it is swung back and forth in the usual pendulous fashion before it is released for projection.

It will be noticed too that the walls of the two holes B and C converge in the same direction. The direction of the narrow or palmar walls

10—10 is toward the crown portion 14 on the ball surface. The same is true of the thumb hole D. That is to say, the walls 6 and 8 in this hole D also converge in a direction toward the crown 14. Or, to put it otherwise, the side walls 6 and 8 of each hole converge from the outward transverse wall 12 to the inner transverse or palmar wall 10. This means, therefore, that the natural movement of index and second fingers toward the thumb when the ball is squeezed during the throwing steps is to take advantage of the squeeze in conjunction with the wedging action to absolutely insure a positive grip, yet one which will not, after due experimentation, cause the fingers to needlessly hang in the holes at the moment of ball release.

In adopting the hole shapes shown it is important to stress the fact that a finger more nearly conforms to this grip all during the release of the ball. The grip when thought of as a means of manually grasping and holding the ball, is a grip. But it is a grip only until the last instant of release from the hand; for, at that instant, the thumb naturally comes out of the ball first. Then, the remaining two holes serve as slides or guides as well as suitable grip means to prevent the ball from coming off the fingers at a tangent and causing inaccuracy. Because the human fingers are naturally tapered, this V-slide truly fits the fingers all the way from the larger diameter of the finger at the second joint to the tip of the finger. The wedge shape naturally accommodates the gradual taper of the finger.

To illustrate simply it is only necessary to place the second and index finger in a pair of round holes and withdraw slowly. The fingers only fit the hole when they are completely inserted. As they are withdrawn the finger gradually loses gripping contact with the walls of the holes. Do the same with the improved wedge-shaped lengthwise crotches or guides and the finger has controlled gripping contact all the way out of each socket. This important fact accounts for a more reliable accurate release and a controlled delivery.

A careful consideration of the foregoing description in conjunction with the invention as illustrated in the drawings will enable the reader to obtain a clear understanding and impression of the alleged features of merit and novelty suffi-

cient to clarify the construction of the invention as hereinafter claimed.

Changes in shape, size, materials, number of holes and rearrangement of holes and nominal allowances and tolerances may be, if within the scope of the claim, resorted to in practice.

Having thus described the invention, what is claimed as new is:

In a bowling ball construction, a conventional-type spherical ball having at least two radial sockets converging toward each other and the center of the ball and having their outer ends opening through the convex surface of the ball, said sockets defining complementary holes, one a finger hole and the other a thumb hole, each hole being generally triangular in cross-section and embodying a pair of individual opposed flat side walls and a narrow intervening palmar wall of a width less than the width of the palmar portion of the finger which is opposed thereto and cooperates therewith, said side walls converging toward said palmar wall and defining a substantially V-shaped finger-receiving, retaining guiding and squeezing channel, said channel ranging from the bottom of the hole and opening through the convex surface of the ball and allowing the finger to constantly contact and conform to the general cross sectional shape of the channel and to guide gradually from the hole by way of the channel while having contact with said converging side walls during the withdrawing step until the instant the tip of the finger emerges through the entrance of said hole, the palmar surfaces of the respective holes being disposed inwardly toward each other whereby the respective channels are disposed in opposed wedging relationship resulting in a squeezing action and a resultant efficient grip, yet allowing the fingers to be eased out of the holes when the bowler release the ball.

THOMAS R. UHAS.
